United States Patent

Des. 236,997
Patented Sept. 30, 1975

236,997

TOY AIRPLANE OR THE LIKE

Walter C. Koval, 1206 Woodbrook,
Arlington, Tex. 76011

Filed Apr. 19, 1974, Ser. No. 462,278

Term of patent 14 years

Int. Cl. D21—01

U.S. Cl. D34—15 HH

FIG. 1

FIG. 2

FIG. 3

FIG. 4

FIG. 5

FIG. 1 is a top plan view of a toy airplane or the like showing my new design;

FIG. 2 is a bottom plan view thereof;

FIG. 3 is a side elevational view thereof;

FIG. 4 is a front elevational view thereof; and

FIG. 5 is a rear elevational view thereof.

I claim:

The ornamental design for a toy airplane or the like, as shown.
